UNITED STATES PATENT OFFICE.

WILLIAM H. WINSLOW, OF CHICAGO, ILLINOIS, ASSIGNOR TO WINSLOW SAFETY HIGH-PRESSURE BOILER COMPANY, OF CHICAGO, ILLINOIS, A CORPORATION OF ILLINOIS.

BOILER.

Application filed August 29, 1914, Serial No. 859,157. Renewed November 7, 1917. Serial No. 200,846.

To all whom it may concern:

Be it known that I, WILLIAM H. WINSLOW, a citizen of the United States, residing at Chicago, in the county of Cook and State 5 of Illinois, have invented a certain new and useful Improvement in Boilers, of which the following is a full, clear, concise, and exact description, reference being had to the accompanying drawings, forming a part of 10 this specification.

This invention relates to steam boilers.

The efficiency of a steam plant can, generally speaking, be increased by increasing the working pressure and the working temperature. The efficiency of the steam engine, as is well-known, increases with the temperature range of the motive fluid. Increase of pressure allows a greater output from the engine and within reasonable limits the 15 percentage of frictional losses is considerably reduced. Efficiency of the steam plant is, however, the combined efficiency of the engine and the boiler and any material advance has heretofore been limited by the 20 structure and thermal limitations of the boiler. An increase in the working temperature of boilers heretofore known has resulted in greater radiation losses and heat losses in the stack gases, due to improper 25 construction.

The mechanical strength and the factors of safety have also prevented any considerable increase in pressure, so that raising of the working pressure or temperature, which 30 would be in effect forced firing of the boiler, has been entirely impracticable, due as well to the danger incurred as to the unsatisfactory operation of the boiler under such conditions. The ordinary boiler, when forced, 35 delivers wet steam, which causes not only a decrease in efficiency of the engine, but is dangerous to the operation thereof. Any increase in temperature is also likely to open the seams of the boiler.

The disadvantages of the prior art have 40 prevented a realization of the theoretic efficiencies which could be secured by high pressure superheated steam, as no commercial boiler structure capable of regularly delivering such steam in suitable quantities 45 has heretofore been constructed.

The chief object of the present invention is to provide an improved boiler capable of delivering high pressure superheated steam in large quantities.

Another object is to provide a sectional boiler of integral unitary construction with an improved superheater forming part thereof.

A still further object of my invention is 60 to improve the construction and mounting of the sections of the boiler.

To enable the greatest advantages to be taken of the possibilities of the increased efficiency, as above set forth, I have found it 65 necessary to depart entirely from the prior types of boiler construction, and devise a method of operation and structure for practicing the same fundamentally different from boilers before known.

The present invention is an improvement on the structures disclosed in my prior applications, Serial No. 656,179, filed October 23, 1911, patented Aug. 14, 1917, Patent Number 1,237,233, and Serial No. 841,445, filed May 28, 1914, patented Aug. 14, 1917, Patent Number 1,236,641.

Figure 1 of the drawings is a diagram explaining the action of a boiler constructed 80 in accordance with my invention.

Figure 2 is a cross sectional view of a boiler embodying my invention.

The boiler is of the sectional type having a plurality of similar sections, one of which is shown in elevation in Figure 2. The section consists of a header 1 to which a number of tubes are welded to form an integral structure. A front header 2 is welded to a number of these tubes in the same manner. An auxiliary header 3 is welded to the uppermost tubes 4 which are longer than the tubes 5 connecting the headers 1 and 2. The tubes 5 are given a slight curvature, which has been shown in exaggerated form in the drawing, to relieve the tubes of the effect of unequal expansion, that is, by giving these tubes a slight curvature the column effect thereof is destroyed. The tubes 4 are shown as being straight, although the same might be given a slight curvature if desired.

Each section has a feed water connection 6 to a common supply pipe 7 and a steam con-

nection 8 to a common steam header 9. Unions 10 allow of convenient connection and disconnection of the feed pipe 6. The steam pipe 8 is also provided with a union 5 in the form of a ground ball joint 11 to provide a tight joint even under the effect of contraction and expansion due to heating. This joint comprises fittings 12 provided with spherical seats in which is fitted a 10 lens shaped washer 13 having a passage therethrough.

A strap 14 surrounds the fittings 12 and is provided with a threaded brass block 16 and a set screw 17 for forcing the two fittings 12 against the packing 13. Slight movements of the fittings are possible without causing an opening of the joint.

The header 1 has welded at the bottom end thereof a steel forging 18 which is provided with a flange 19 at the bottom thereof. The forging 18 is of considerably greater weight than the body of the tube 1 and has seats for the plugs 20 opposite the two lowermost tubes 21. These plugs 25 20 may be removed for the purpose of cleaning the tubes 21. The lower side of the flange 19 is provided with a spherical seat forming part of the ground joint between the header 1 and the mud drum 22.

30 The mud drum 22 is provided also with a spherical seat 24 between which seat and the forging 19 a lens shaped packing washer is provided for forming a tight joint.

Flanges 25 connected to the mud drum 22 35 provide sockets for the bolts 26 which clamp the mud drum and the forging together. The mud drum 22 is common to all of the sections and is provided with a common blow-off connection 27 containing a valve 28.

40 A suitable boiler setting or casing 30 surrounds the boiler. This casing is provided with a fire box 31 and a smoke stack 32 at opposite ends of the boiler. Any type of burner may be employed in the fire box but 45 I have shown the grates 33 as indicating a typical furnace construction.

A baffle plate 34 is connected to each one 50 of the sections and these plates form a complete wall transversely of all the sections. The rear of the fire box is closed by a baffle wall 35 upon which the baffle plates 34 rest, the whole structure constituting in effect one continuous wall.

A fire flue 36 connected to the front end 55 of the fire box leads upward between the front wall 37 and the front headers 2. The sections of the boiler are set close together so that the headers are in contact and the headers 2 form a practically tight wall for the 60 smoke flue 36. The upper end of the flue 36 is obstructed to a certain degree by the superheating tubes 4 which are longer than the tubes 5 and extend to the front of the wall 37. A space 38 is formed between the 65 roof 39 of the casing and the tubes 4 to

allow the gases passing through the flue 36 to pass toward the rear of the boiler and spread over the tubes 4 before passing downward between the baffle 34 and the rear headers 1.

The amount of furnace gases passing through the flue 36 is controlled by the damper 48. The damper is mounted on the rod 49 which can be moved to set the damper in any desired position by means of the 75 quadrant 50. In this manner the degree of superheating can readily be controlled.

The major part of the furnace gases is conducted upward across the tubes 5 over the baffle 34 and down through the space between the baffle 34 and the rear header 1 to the smoke box 40.

All of the gases from the fire box 31 must pass between the baffle 34 and the headers 1 into the smoke box at the rear of bridge wall 35 before passing to the smoke flue 41 and out of the stack 32.

Thus they pass through the economizing portion of the boiler before passing to the stack 32. The feed water connections 6 may 90 be coiled or suitably bent to expose a more extensive surface to the stack gases in order to extract as much of the remaining heat as possible before the gases are finally exhausted.

These economizer sections are individually removable with the individual boiler sections.

The weight of each of the boiler sections is supported entirely from its header 1. The header rests upon the mud drum 22 which receives the downward thrust of the entire section. The section is supported against tilting edgewise by a Z-bar 42 which is mounted on the upper part of the boiler setting and engages the tops of each of the headers 1. The tubes 5 form a strut for supporting the weight of the boiler and for supporting the weight of the superheater as well. A metal peg 43 is welded to the lower tube 4 of the superheater and rests upon the top of the header 2. The peg is not attached to the header 2 and thereby differences in expansion due to heat may occur without straining the parts.

The back of the boiler casing contains a door 45 through which the sections may be withdrawn when it is desired to make replacements or repairs. A plate 46 covers the front of the boiler and rests upon the roof 39 and the cornice 47 of the front of the boiler so as to be readily removed to allow withdrawal of the steam connection 8 and the fitting 12. To remove a section it is necessary merely to open the door 45, disconnect the said connection 6, the bolts 26 at the mud drum, and the strap 14 at the steam connection. The section may then be readily withdrawn. Each one of the sections even in large sizes is light enough that it 130

can be manipulated by a single attendant and in this manner repairs or replacements are readily and quickly effected.

In operation the headers 1 and 2 are only 5 partially filled with water and, as a result, only the lowermost tubes contain water. The heat from the furnace causes the water to expand and also to generate steam bubbles and as a result the water in the header 2 rises 10 above the level in the header 1 and the "cataract" effect described in full in my Patent No. 1,236,641 issued August 14, 1917, take place. The tubes 5 are all heated to a very high temperature but the upper tubes 15 are of a higher temperature than the lower ones because of the cooling effect of the water in the lowermost tubes and the consequent more rapid withdrawal of heat thereby. As a result, the water which flows back 20 in the inclined tubes goes off into steam readily and under the most favorable conditions for producing dry steam. The uppermost tubes 5 which are substantially horizontal are drying tubes for drying and super- 25 heating the steam as it passes from the lower tubes to the top of header 1.

The tubes 4 are purely for superheating purposes and it is to secure this effect that the fire flue 36 is constructed to lead the hot 30 furnace gases directly to the top of the boiler section.

The expansion of the tubes 4 will be greater than of the tubes 5, as the tubes 4 contain only dry steam which is being superheated. 35 Furthermore, these tubes are of a greater length and a consequent greater total amount of expansion occurs. It is desirable, therefore, that these tubes be connected to the separate header 3 as shown. It will be noticed that the steam flowing in the super- 40 heater tubes 4 flows in the direction opposite to that of the furnace gases and, in fact, the entire boiler structure is constructed to lead the hot gases and the water for forming steam in generally opposite directions so that 45 the steam is delivered at practically the temperature of the furnace gases and the furnace gases are exhausted at practically the temperature of the incoming water. This is the ideal condition for transmitting the maximum amount of heat from the gases to the steam.

The action occurring within the boiler may best be explained by reference to Figure 1, which is a diagrammatic representation of the boiler. It is to be understood that Figure 1 is entirely diagrammatic and is not intended to cover or disclose the actual structure of the boiler. Let it be assumed that 50 the lowermost tubes are grouped into a pair of tubes, which are shown as the bottom tubes in Figure 1. The intermediate tubes are grouped into a single tube, which is shown in Figure 1 on a second level. The 55 group of tubes which are substantially hori-

zontal, connected at the top of header 2, are shown in the diagram as being grouped into a single tube. The uppermost tubes connecting the auxiliary and rear headers are shown as grouped into a single tube at the top of the figure. The major portion of the heat is applied to the section at the lower left-hand corner of the boiler in proximity to the fire-box. As indicated in the figure, there are two distinct paths for the furnace gases, 70 which are represented in this figure by heavy wavy arrows. One path leads upward along the front header through the superheating zone, down through the drying zone, and separating zone, to the economizer, from 75 whence this part of the gases passes on to the stack. The major portion of the furnace gases passes up through the circulating and separating zones, over the baffle, and passes down through the economizing zone and 80 thence to the stack. It is to be understood, that this path for the gases contains also the drying zone of tubes, and these tubes are subject to the action of both currents of 85 gases. 90

As a result of the heat applied to the lowermost tubes, a violent boiling action occurs in the circulating zone, raising the level of the water in the front header to a height considerably above that in the rear header 95 and causing a rapid circulation in the lower pair of tubes as indicated by the arrows. This is due, first, to the difference in specific gravity of the heated water and the relatively cool feed water and to the fact that the 100 steam bubbles in attempting to free themselves from the water lift a considerable portion of water above the normal level in the rear header. As a result, the water so lifted is caught in the open tubes and is conducted 105 back to the rear header over the hot tubes in an ideal condition for forming steam, as well as separating out mechanically from the water the bubbles of steam already 110 formed. The steam formed in the circulating and separating zones passes upward through the drying zone and it is only by passing through this zone that the steam is enabled to pass to the superheater and out 115 of the main connection. It is thus impossible for any moist or wet steam to escape to the steam connection. 120

It will be noticed that one current of gases is led in the same direction as the current of water passing off into steam. This is the current of gases passing across the tubes and over the baffle. Another current of gases passes parallel to the current of steam, but in an opposite direction. In this manner a maximum steam forming and circulating action is obtained by the one current and a maximum drying or superheating effect is obtained by the other current. 125

A boiler constructed in accordance with the above teachings is capable of delivering 130

- high pressure superheated steam at a very rapid rate. The sections have a very large factor of safety due to the welded construction throughout and the absence of any joint subject to the action of the hot furnace gases. The boiler comprises distinct zones of action, including the main circulating and steam producing action in the bottom tubes, especially at the left-hand side of the section. A separating action of the steam and water occurs above the main level of the water in the boiler and a superheating action occurs in the upper tubes 5 and in the superheater tube 4. The incoming feed water is heated in the zone defined by the baffle 34 and the header 1, as well as the feed water connection 6, where the outgoing furnace gases give up the remaining available heat.
- It will be noticed that I obtain in a single welded structure the four distinct operations and am enabled as well to reverse the flow of steam in the superheating tubes so as to secure a maximum superheating effect.
- The action of the gases passing through the flue 36 may be regulated by the damper 48. This damper is especially valuable in causing a quick formation of steam when the boiler is first fired up. By closing the damper 48, all of the gases from the fire-box are forced through the tubes containing water and, in this manner, the boiler may be brought up to full pressure in a minimum period of time. As soon, however, as steam is to be drawn from the boiler, the damper 48 may be opened to subject the tubes 4 to the furnace gases for obtaining suitable superheat.
- Although I have described my invention with reference to a particular embodiment as required by the statutes, I do not intend thereby to limit the invention to any of the details shown or described, as it is evident that numerous modifications will at once be apparent to those skilled in the art and I desire that all such modifications be considered as coming within the spirit and scope of the present invention.
- What I claim as new and desire to secure by Letters Patent of the United States is:
1. In a boiler, a plurality of closed unitary sections adapted to be exposed on all sides to high temperature gases and each including a rear header having a continuous unobstructed passage therethrough, a front header, a plurality of tubes connecting said headers, the lowermost of said tubes for containing water and the uppermost tubes for containing steam, a third header and a plurality of substantially horizontal tubes connecting said first and third headers, a common mud drum connected to said first header and a common steam drum connected to said third header.
  2. In a boiler, a plurality of sections in-

cluding a vertical rear header having a continuous unobstructed passage therethrough, a second header, a plurality of inclined tubes connecting said headers, the lowermost of said tubes being filled with water, a third header arranged beyond the second header, a plurality of substantially horizontal tubes connecting said first and third headers, the tubes connected to said third header being longer than the tubes connected to said second header, and constituting a superheating part adapted to be arranged in the direct path of fire gases, a common mud drum connected to said first header and a common steam drum connected to said third header.

3. In a steam boiler, a plurality of sections, each of said sections including a header having an unobstructed passage throughout its length, a second header, a plurality of inclined tubes connecting said headers, a third header, a plurality of horizontal tubes connecting said third and said first headers, a furnace and setting for said boiler, the sections having their corresponding headers in contact to form a wall, a flue formed between said headers and a wall of the setting, the tubes connecting the first and third headers being longer than the tubes between the first and second headers and extending over said flue.

4. In combination, a boiler comprising a plurality of sections, each of said sections comprising a front header, a rear header and an auxiliary header, and tubes connected to said headers, a setting for said boiler forming a casing, a furnace in said setting adjacent the front of said sections, a smoke flue in said casing at the rear of said sections, a space being formed between the front wall of the furnace and the front headers to form a fire flue, the rear headers forming a wall of said smoke flue and the tubes connected to said auxiliary header extending over said fire flue so that the gases from said flue pass through said tubes.

5. A boiler section comprising a front header, a rear header of greater length, an auxiliary header, inclined tubes connecting the front and rear headers and substantially horizontal tubes connecting the auxiliary header and the rear header, said tubes being of greater length than the inclined tubes, all of the tubes lying in substantially the same plane, and constituting a jointless metallic structure adapted to be exposed on all sides to high temperature gases of combustion.

6. In a boiler, a section comprising a front header, a rear header and an auxiliary header, inclined tubes connecting said front and rear header and substantially horizontal tubes connecting the auxiliary and the rear header, said tubes being of greater length than the inclined tubes, all of the tubes lying in substantially the same plane,

a steam connection to the auxiliary header and a water connection to the rear header, and a mud drum supporting the weight of said section.

5 7. A boiler section comprising front, rear and auxiliary headers, tubes connecting the headers, said tubes and headers lying in substantially the same plane, a mud drum connected to the rear header and bearing substantially the entire weight of the section.

10 8. A boiler comprising a plurality of sections, each of said sections having front, rear and auxiliary headers, tubes connecting said headers, said tubes and headers lying in substantially the same plane and all of the tubes connected on one side of the rear header, a steam drum connected to the auxiliary header, a feed water connection to the rear header and a setting enclosing the 20 boiler, sections having their rear headers supported by the boiler setting and an abutment on said setting bearing against the side of the rear header for preventing the section from tilting.

25 9. In a boiler, a plurality of sections, each of said sections comprising a pair of main headers and an auxiliary header, tubes connecting said headers lying in substantially the same plane, means to support said sections comprising a bearing below one of the main headers to bear the weight of the section, and a support to prevent tilting of the section.

30 10. In a boiler, a plurality of sections, a casing around said boiler having a fire-box and a smoke flue, each of said sections comprising a front header and a rear header, a plurality of inclined tubes connecting said headers, said headers and the lowermost 40 tubes being filled with water, an auxiliary header, substantially horizontal superheating tubes connecting said rear header and said auxiliary header, a fire flue between the walls of said casing and said front header, said flue leading to said superheating tubes, and a baffle between the fire-box and the smoke flue forming a passage from said fire-box up through the tubes between the front header and the baffle and down between the 45 baffle and rear header.

50 11. A boiler section comprising a front and a rear header, said rear header being longer than the front header, a plurality of inclined tubes connecting the bottom portions of said headers, a substantially horizontal tube connecting the upper portions of said headers, a support for said longer header carrying the weight of the section, and a support preventing tilting of the section.

55 12. A boiler section comprising a front header, a rear header, said rear header being of greater length than said front header, and an auxiliary header, a plurality of tubes connecting said front and auxiliary headers

to said rear headers, the tubes connecting said auxiliary header and said rear header being substantially horizontal, the tubes connecting said front and rear headers comprising a plurality of inclined tubes connecting the lower ends of said front and rear headers, a substantially horizontal tube connecting the upper ends of said front and rear headers, said horizontal and inclined tubes forming a strut and supporting means for 70 said rear header carrying the weight of the section, and a support preventing tilting of the section.

75 13. A boiler comprising a plurality of sections, each of said sections comprising a front header and a rear header, a plurality of inclined tubes connecting said headers, said headers and the lowermost tubes being filled with water, an auxiliary header, substantially horizontal superheating tubes connecting said rear header, a casing around said boiler having a fire-box and a smoke flue, a fire flue between the walls of said casing and said front header, said flue leading to said superheating tubes, and a damper in said fire flue for regulating the flow of gases in said flue.

80 14. In a boiler, a plurality of sections, a casing surrounding said sections, a furnace and a smoke flue connected to said casing, said boiler and casing having means to cause part of the fire gases to flow in the same direction as the water circulation and to cause another part of the fire gases to flow in the opposite direction to the steam flowing out of the boiler, thus exposing the steam to the maximum heat at substantially the point of delivery.

85 15. In combination, a front and a rear header, one of said headers projecting downward beyond the other, a plurality of inclined tubes connecting the bottom parts of said headers, a substantially horizontal tube connecting the upper part of said headers, a support for the bottom of said one header to 105 carry substantially all the weight of the section and a support near the top of said one header for preventing tilting of the section.

90 16. In combination a front and a rear header, one of said headers projecting downward below the other, a plurality of inclined tubes connecting the bottom portion of said headers, a substantially horizontal tube connecting the upper portion of said headers, a support for the bottom of said one header to 110 carry substantially all the weight of the section, a support near the top of said one header for preventing tilting of the section, and a superheater connected with said one header and resting upon said other header.

115 17. In a boiler and superheater section, a longer header, a shorter header, said headers being substantially vertical, an inclined lower tube joining said headers near their bottom portion, a substantially horizontal tube 120 125 130

joining said headers at their upper portion, a superheater connected to said longer header and projecting over and beyond said shorter header, a support beneath said longer header and a support adjacent the upper end of said longer header to prevent tilting of said section.

18. A boiler comprising a plurality of sections, each of the sections comprising a supported vertical header, a plurality of tubes extending from one side of the header, a second header joining the ends of the tubes, a third header above the second header and other tubes joining the third header with the first header, the second and third headers and said tubes being all supported by and upon said supported header.

19. A boiler comprising a plurality of sections, each of said sections having vertical

front and rear headers joined by a plurality of tubes lying substantially in the same vertical plane, a mud drum connected to the lower end of the rear header and upon which said header is supported, the lower tubes constituting a strut and the upper tubes tension members for supporting the tubes and forward header upon said rear header.

20. A boiler comprising a plurality of sections, each section comprising rear and front vertical headers, and substantially horizontal tubes connecting the headers, a support below the sections at one end, the top of said supported end adapted to be held horizontally against an abutment by the weight of the section.

In witness whereof, I hereunto subscribe my name this 9th day of June, A. D. 1914.

WILLIAM H. WINSLOW.
